TROPHY CUP OR SIMILAR ARTICLE

Thomas H. Jones, Washington, D. C., assignor to the United States of America as represented by the Secretary of the Army

Application March 24, 1950, Serial No. 8,736

Term of patent 14 years

(Cl. D29—28)

To all whom it may concern:

Be it known that I, Thomas H. Jones, a citizen of the United States and resident of the city of Washington, in the District of Columbia, have invented a new, original, and ornamental Design for a Trophy Cup or Similar Article, of which the following is a specification, reference being had to the accompanying drawings, forming a part thereof.

The essential features of my design are shown in full lines.

I claim:

The ornamental design for a trophy cup or similar article, substantially as shown and described.

THOMAS H. JONES.
